UNITED STATES PATENT OFFICE.

ISAAC STUHLMAN, OF CHICAGO, ILLINOIS.

SEWING-MACHINE GUIDE.

No. 873,332.

Specification of Letters Patent.

Patented Dec. 10, 1907.

Application filed April 21, 1900. Serial No. 13,700.

To all whom it may concern:

Be it known that I, ISAAC STUHLMAN, a citizen of the United States, residing at Chicago, in the county of Cook and State of Illinois, have invented certain new and useful Improvements in Sewing-Machine Guides, of which the following is a full, clear, and exact specification.

My invention relates to guides for sewing machines and it has for its primary object to provide a guide that will automatically yield when striking into a corner of the edge of the goods, such for instance as that which occurs in the notch of a coat lapel, thus permitting the goods to pass under the needle past such corner sufficiently far to reach the proper marginal distance for the edge stitching that runs off at an angle to the right or left. With these ends in view my invention consists in certain features of novelty in the construction, combination and arrangement of parts by which the said objects and certain other objects hereinafter appearing are attained, all as fully described with reference to the accompanying drawings and more particularly pointed out in the claims.

In the said drawings, Figure 1 is a perspective view partly broken away of a sewing machine head having my improved guide applied thereto, the view being taken from the rear. Fig. 2 is an enlarged detail sectional view taken through the upper joint of the arm which supports the guide. Fig. 3 is a detail sectional view taken through the lower joint of said arm. Fig. 4 is a plan view of the presser foot and guide, the movable member of the presser foot being turned up. Fig. 5 is a transverse sectional view of the presser foot with the movable member turned down. Fig. 6 is a detail sectional view of a part of the presser foot showing the stop for limiting the upward movement of the movable portion. Fig. 7 is a transverse section taken on the line 7—7 Fig. 4. Fig. 8 is a vertical longitudinal sectional view of the guide stem and guide showing the device for locking the guide in place. Fig. 9 is a detail transverse section taken on the line 9—9 Fig. 8 showing the supplemental guide in its turned-up or inactive position. Fig. 10 is a similar view showing the supplemental guide turned down in its active position, and Fig. 11 is an enlarged detail sectional view of the dog for holding the gages hereinafter described.

1 represents a stem upon the outer end of which is mounted the guide proper 2 which has a straight edge or end adapted to abut against the edge of the goods 3 for guiding the same under the needle 4 and forming a line 5 of stitching very close to such edge. When a corner such as shown at 6, in the edge of the goods is reached it is evident that the guide 2 must either be withdrawn or yield to permit the goods to pass far enough under the needle to reach the marginal distance represented by the dotted line 7 of the seam or line of stitching which turns to the right of the line 5.

In order that the guide 2 may always remain in place and serve to guide the needle around the corner 6 and thus avoid the necessity of stitching around such corner by the aid of the eye alone, I make the guide 2 yield on its stem 1 so that it will move rearwardly a sufficient distance with the goods to enable the latter to come under the needle until the line 7 is reached. In order to accomplish this the upper side of the guide 2 is provided with a dove-tailed rib 8 which slides in the under side of the stem 1 lengthwise of the line of stitching 5 or transversely of the stem 1 and projecting upwardly from this rib 8 is a pin 9 which slides back and forth in a transverse slot 10 formed in the stem 1 and containing a spring or cushion 11 which bears against the pin 9 and serves to hold the guide 2 in its normal position. In order that the guide may be firm while the straight edge is being stitched it is locked by means of a latch 12 having an eye or aperture in one end which fits down over the pin 9, its other end being pivoted at 13 to the upper side of the stem 1 and having a heel-piece 14 which bears against a spring 15 mounted on the stem 1 so that the latch will be held in place when turned down and will also be held up out of engagement when turned up. In the use of the device the latch 12 will be turned up out of the way when the corner 6 is reached, thus permitting the guide 2 to yield as required and when the corner is passed and the guide resumes its normal position under the influence of the spring 11 the latch 12 is again thrown down to engage the pin 9.

When it is desired to run the seam 16 or to do quilting or to run any seam or line of stitching at a distance from the edge of the goods, requiring the goods to be placed under the guide 2, the guide is elevated by any suitable means but preferably by the means

which I shall presently describe and the goods passed under it and it is also set inwardly or towards the right so that it will be approximately over the last seam or line of stitching while the needle is in the proper place for making the next line of stitching and a supplemental guide 17 is then turned down and the goods adjusted until the last line of stitching falls directly under the point 5 of the guide 17 when the presser foot may be lowered and the goods adjusted in the position for the next line of stitching. This supplemental guide 17 is hinged to the guide 2 by means of a pin 18 and it is so arranged 10 that when not in use it may be turned over on top of the guide 2 as clearly shown in Fig. 9 and when desired for use may be turned down in front of the guide 2 as shown in Fig. 10, the bottom of the mortise 19 in which the 15 supplemental guide 2 lies being beveled at 20 to hold the guide 17 at the requisite angle and the guide 17 being slotted as shown at 21 where the pin 18 passes through it so as to yield upwardly to permit irregularities in the 20 goods to pass.

The stem 1 passes through a pair of keepers 22 mounted on a horizontal plate 23 and projects across the bottom flanges 24-25 of two independently adjustable gages 26-27 each 25 having a vertical flange 28-29 provided with a notch 30-31 and the stem 1 is provided with a dog 32 adapted to be dropped into either of the notches 30-31 and thus hold the guide in position. As shown in Fig. 1 30 the dog 32 is in the notch 31 which holds the guide 2 in proper position for running the stitching 5. When it is desired to run the next line of stitching further removed from the edge of the goods the dog 32 is lifted out 35 and dropped into the notch 30 whose gage 26 has been previously set for the proper distance between the stitching 5-16. Thus it will be seen that the guide 2 may be readily changed from one position to the other and 40 the seams on all garments will be uniform. The dog 32 is formed on a lifting head 33 provided with a stem 34 which projects downwardly through the stem 1 and has a lug 35 engaging in a socket 36 in the plate 23 for 45 better holding the stem 1 in position, the spring 37 being interposed between the top of a casing 38 in which the stem 34 is located, and a pin 39 in the stem 34 for automatically pulling the stem 34 downward.

The plate 23 is supported by an arm 40 whose upper end is mounted on an eccentric 41, see Fig. 3, having a thumb head 42 and a screw 43 which passes through the lower end 50 of an arm 44 and a nut 45 by means of which the eccentric 41 may be locked in place. By this means it will be seen that when the head 42 is turned the plate 23 will be raised and the guide 2 consequently lifted the requisite 55 distance to permit the goods to pass under it and under the plate 23 also if desired.

The upper end of the arm 44 is pivoted between two ears 46 on a divided collar 47 which may be clamped or otherwise secured to the sewing machine arm 48, 49 being the pivot which supports the arm 44, and 50 is a spring which is coiled around the projecting ends of the pivot 49 and passes through perforations 51 therein and thence passes downwardly in front of the arm 44 so as to exert a normal tendency to force the arm 44 upwardly under the sewing machine arm 48, the arm 44 being curved to the contour of the under side of the arm 48 so as to fit closely thereto while the arm 40 is curved to the contour of the under side of the arm 44 so that it 70 may be folded closely to the under side of the arm 44 and thus bring the plate 23 and the mechanism supported thereon up under the arm 48 and out of the way. The spring 50 is designed to throw the arm 44 and connected parts up in the described manner as soon as the catch 52 is withdrawn. This catch 52 passes through one of the ears 46 and engages in the arm 44 as clearly shown in Fig. 2, a coil spring 53 surrounding the catch 52 to force it 80 normally inward.

The presence of the guide 2 so close to the presser foot when the edge stitching 5 is being made necessitates the presser foot being made in two parts so that one portion may be 95 turned up to give place to the guide 2. Referring to Figs. 4 to 7 inclusive, 54 represents the leg of the presser foot and 55 is the presser foot proper or stationary part secured thereto in any suitable way while 56 is the 100 movable or hinged part. The part 56 is provided with a hub 57 which is hinged by means of a pin 58 to the side of the part 55 so that the part 56 may be turned into a vertical position as shown in Figs. 4 and 7 to give 105 place to the guide 2 which is moved up into close proximity to the presser foot 55 when the edge seam 5 is to be run. A coil spring 59 is passed around the boss 69 and secured to the member 55 in any suitable way at one 110 end while the other end is passed downwardly and engaged under the heel of the member 56 as shown at 60 so that when the member 56 is unrestrained the spring 59 will throw it up into the position shown in Fig. 7. 115

In order that the member 56 may be held down in position when desired I provide a latch which has a beveled head 61 arranged on the upper side of the foot member 55 and projecting slightly beyond its edge so that when the member 56 is forced downwardly it will first deflect the head 61 and then engage under it. The latch is provided with a stem 62 mounted in a keeper 63 on the upper side of the member 55 while the head 61 is mounted in a keeper 64, a coil spring 66 being interposed between the head 61 and keeper 63.

The foot member 56 is limited in its upward movement by a lug 67 formed on the hub 57 and engaging with a lug 68 formed 130

on a boss 69 projecting from the side of the member 55.

Having thus described my invention what I claim as new therein and desire to secure by 5 Letters Patent is:

1. The combination in a sewing machine of a stitching means, a guide having its guiding end independently movable lengthwise of and in the direction of movement of the goods 10 and cushioning means for resisting the movement of said independently movable end, substantially as set forth.

2. The combination in a sewing machine of a stitching means, a guide having its guiding end independently movable lengthwise of the line of stitching, cushioning means for resisting the movement of said independently movable end and a catch for locking said independently movable end in place and holding 20 it against movement lengthwise of the line of stitching, substantially as set forth.

3. The combination of a sewing machine, of a stitching means, a bodily liftable guide and a supplemental guide hinged to said 25 bodily liftable guide, adapted to project below said first guide and free to gravitate upon the goods.

4. The combination in a sewing machine of a bodily liftable guide, a supplemental 30 guide and a sliding and pivotal joint connection between said liftable guide and supplemental guide, with a stitching mechanism, substantially as set forth.

5. The combination in a sewing machine 35 of a bodily liftable guide, a supplemental

guide supported on and carried by the first guide, a loose joint connecting said supplemental guide with the forward side of said first guide and means for limiting the downward movement of said supplemental guide, 40 with a stitching mechanism, substantially as set forth.

6. The combination in a sewing machine of a guide, having the guiding end independently movable lengthwise of and in the direction of movement of the goods, with a presser foot having an independent portion 45 on the side adjacent to said guide, movable upwardly above the independently movable end of the guide, so that the latter may pass 50 under it, substantially as set forth.

7. The combination of a sewing machine, of a stitching means, a bodily liftable guide, a supplemental guide pivoted to said bodily liftable guide, said supplemental guide being 55 adapted to be projected below said first guide, and means for holding the supplemental guide out of operative position.

8. The combination of a sewing machine, of a stitching means, a bodily liftable guide, 60 a supplemental guide pivoted to said bodily liftable guide and adapted to project below said first guide, and means for yieldingly holding said supplemental guide in its projected position.

ISAAC STUHLMAN.
